United States Patent Office

Des. 203,895
Patented Feb. 22, 1966

203,895

CAP FOR A DISPENSING CAN

Godfrey H. Klun, Parma, Ohio, assignor to Union Carbide Corporation, a corporation of New York

Filed Apr. 16, 1965, Ser. No. 84,840

Term of patent 14 years

(Cl. D58—26)

FIG. 1.

FIG. 2.

FIG. 3.

FIG. 4.

FIG. 1 is a front elevational view of a cap for a dispensing can, showing my new design;

FIG. 2 is a top plan view thereof;

FIG. 3 is a side elevational view thereof; and

FIG. 4 is a rear elevational view thereof.

I claim:

The ornamental design for a cap for a dispensing can, substantially as shown.
